ALPHEUS E. ROE, OF OAKLAND, CALIFORNIA

CAN-FILLING MACHINE

Application filed May 2, 1928. Serial No. 274,480.

My invention relates to an apparatus for filling containers with measured quantities of liquid.

The principal object of the invention is to provide a machine which is capable of automatically filling a continuously advancing procession of containers with measured quantities of liquid in the least possible time and without waste of liquid.

10 Other objects of the invention are to provide an apparatus in which evaporation losses are reduced to a minimum, to provide means for adjusting the volume of liquid supplied to each container, and to provide means for quickly changing from one source of liquid supply to another. Still further objects and advantages of the invention will become apparent from the following specification, which should be read with the understanding

15 that the form, construction and arrangement of the several parts of the apparatus may be varied, within the limits of the claims hereto appended, without departing from the spirit of the invention as set forth in said claims.

20 My invention as herein described, and illustrated is especially adapted for filling standard five-gallon cans with such liquids as gasoline, kerosene, and oils, although it may readily be adapted for filling other containers

25 with other liquids.

The machine comprises, broadly, a continuously rotating turret structure capable of holding a considerable number of cans, and by which the cans are continuously advanced in a procession. The measuring and filling instrumentalities are carried by the turret, and are automatically operated during its circular movement. The empty cans are brought to the turret, and the full cans removed therefrom, by suitable conveying means. The cans are fed to the turret, filled, and removed successively, and the operation may be carried on continuously.

30 A more detailed description of the machine will now follow, with reference to the accompanying drawings, wherein:

Fig. 1 is a partly broken and partly diagrammatic plan view.

35 Fig. 2 is a central vertical section,

Fig. 3 is an enlarged vertical section through one of the measuring chambers.

Fig. 4 is a vertical section of the float controlled supply valve.

Fig. 5 is a detailed front elevation, enlarged, of one of the can-holding chairs.

Fig. 6 is a detailed part sectional elevation, enlarged, of the stem and cam roller of one of the measuring chamber filling valves.

Referring now more particularly to the drawings, the reference numeral 1 designates a continuously rotating turret structure, supported upon wheels 2. Empty cans E are brought to the turret 1 by a conveyor indicated diagrammatically at 3, in Fig. 1, and are successively placed upon said turret by any suitable means not shown. It may be assumed for purposes of the present description, that the cans are placed upon the turret by an attendant. The periphery of the turret is provided with an annular row of chairs 4 in which the cans are placed and by which they are suitably positioned. Each chair 4 is vertically movable upon the turret, being slidably mounted upon a pair of guide rods 5, Figs. 2 and 5, and provided with a roller 6 which runs for a part of the revolution of the turret upon a fixed semi-circular cam, or track 7. This track, which has inclined ends 7', Fig. 5, is slightly elevated, so that the chairs 4 and the cans resting thereupon are raised, during a part of the revolution of the turret, for a purpose to be explained later.

During the remaining portion of the revolution of the turret the chairs 4 rest upon a ring or flange 8, Fig. 2, forming part of the bottom of the turret, and are maintained at the level of the conveyor 3. The ring 8 may be provided with gear teeth adapted to mesh with a pinion 9, by which the turret is rotated. A second conveyor of any suitable construction, indicated diagrammatically at 10 in Fig. 1, receives the full cans F from the chairs 4 and carries them away. A fixed stripper 11 serves to transfer said full cans

95 from the chairs 4 to said discharge conveyor 10. While on the continuously rotating turret 1, the cans are filled, each with a measured volume of liquid, by mechanism which will now be described.

The turret 1 supports, above the chairs 4, an annular tank 12 which rotates with said turret and contains a supply of the liquid, (Figs. 1 and 2). Radially disposed pipes 13 connect said annular tank with a central float chamber 14, which receives the liquid from outside sources. The rotating chamber 14 is closed at the top by a relatively stationary valve head 15, Figs. 1, 2, and 4, a suitable bearing 16 being provided between said chamber and said valve head. A connection is provided to enable liquid from several different sources to be supplied to said head 15. One example of such connection is shown in Figs. 1 and 2 as comprising a flexible conduit 17 secured to the head 15 and adapted for separable connection, by partially rotating said head, with any one of a number of radially arranged pipes 18 leading from different sources of supply. Therefore when it is desired to fill cans with kerosene, for example, the flexible conduit 17 is connected with that pipe 18 leading from the kerosene supply reservoir, and when it is desired to fill gasoline, said conduit is moved to the gasoline supply pipe, and so on. Suitable shut-off valves are indicated at 19, and blind flanges or caps 18' are provided for temporarily and positively closing the pipes 18 which are not in use. The head 15 is provided with a suitable valve 20, Fig. 4, here indicated as a balanced piston valve of well known form, which is operated by a float 21 lying within the central chamber 14. The valve 20 and float 21 automatically maintain the liquid in the chamber 14 and the annular tank 12 at a constant level, as indicated in Fig. 2.

Depending from the bottom of said annular tank are a series of measuring chambers 22, one positioned above each can chair 4. These chambers are preferably made of glass, to enable the liquid to be observed, and are clamped between upper and lower heads 23 and 24 and secured to the bottom of the tank by rods 25, as shown in Fig. 3.

Depending from the bottom of each measuring chamber 22 is a discharge nozzle 26 positioned directly above the filling aperture 27 of the can positioned on the corresponding chair 4. The lower end of said nozzle is provided with a resilient ring 28 of felt or similar material adapted to contact with the top of the can when the latter is raised by the vertical movement of its chair. Vent apertures 29 are provided between the contact ring 28 and the nozzle to permit the escape of air from the can while being filled. The nozzle 26 is in the form of a sleeve and is slideable vertically upon a tube 30 secured to the lower head 24 of the measuring chamber. A valve 31 is provided in said tube for opening and closing the outlet of the measuring chamber, and said valve is connected with the slideable nozzle 26 by a rod or stem 32, so that

it is opened and closed by the vertical movement of the can. The vertical position of the chair 4 as it passes the conveyor 3 is such that the empty can E will slide freely beneath the nozzle 26. The subsequent elevation of said chair and the can, as described above, causes the lower end of the nozzle to enter the filling aperture 27 of the can, and then opens the valve 31 by the movement of said nozzle, thus allowing the liquid to flow from the measuring chamber 22 into the can. 75

The can is not lowered until sufficient time has elapsed for all the liquid to flow out of the chamber 22. In order to adjust the volumetric capacity of said chamber, the tube 30 is adapted to be raised or lowered, preferably by being screwed into the lower head 24, as shown at 33 in Fig. 3. Thus, if the tube 30 is elevated to project into the chamber, the volume of liquid discharged therefrom will be reduced. Suitable marks, not shown, may be placed upon the tube 30 to indicate its position in terms of the effective volumetric capacity of the chamber. 80

A valve 34, Fig. 3, is placed in the upper head 23 of each measuring chamber to open and close communication between the annular tank 12 and said chamber. This valve is operated by a stem 35 which extends upwardly and has a roller 36, Figs. 2, and 6, following a fixed cam track 37 mounted above the tank upon brackets 38 and provided with downwardly inclined ends 37'. The valve stem 35 has a central bore terminating in a lateral aperture 39 positioned above the level of the liquid in the tank, thus providing a vent for the escape of air from the measuring chamber 22 into said tank while said chamber is being filled. The tank is provided with a cover 40 to prevent evaporation, and by venting the chambers 22 into said tank instead of into the atmosphere, evaporation losses are still further reduced. The cam track 37, as shown in Fig. 1, extends approximately through the second half of the circular travel of the turret 1. Therefore, after any given chair 4 is lowered by its roller 6 passing off the rear end of the track 7, so that the discharge valve 31 is closed, the filling valve 34 is opened, by the contact of its roller 36 with the track 37, allowing the liquid to flow from the tank 12 into the measuring chamber 22 until the latter is full. The valve 34 is again closed before the discharge valve 31 opens. 100

Thus during approximately the first half of the revolution of the turret, the cans are being filled from the measuring chambers, and during the second half of said revolution the measuring chambers are being filled from the annular tank 12. 120

Certain advantages of my invention will now be pointed out in the light of the preceding description. Since the valves 31 are opened by the cans E, there is no possibility of a valve being opened when there is no 130

can beneath its discharge nozzle. If for any reason a can is not placed upon a chair 4, the corresponding discharge valve 31 will not be opened, and no liquid will be lost. The 5 subsequent opening of the filling valve 34 will have no effect, since the measuring chamber is already full. On account of the construction and relatively small capacity of the supply tank 12, it can be quickly and completely emptied, when changing from one 10 liquid to another, after its supply is cut off at one of the valves 19. The measuring chambers 22 being filled successively, it follows that each, and consequently each can, 15 will be completely filled until the tank 12 is very nearly empty. There will thus be only one, or at most a very few cans which receive a partial charge at the end of a run. The operation of the machine is speedy, continuous, and automatic except for the placing 20 of the cans upon the chairs. And finally, the cans remain beneath the nozzles for a sufficient length of time to insure the recovery of any drip that may occur after the discharge 25 valves are closed, so that there is no waste of liquid. The reduction of evaporation losses to a minimum by covering the supply tank 12 and venting the measuring chambers thereinto has already been mentioned.

30 I claim:—

1. A can filling machine comprising a rotating turret; a vertically movable can holder mounted thereon; a measuring receptacle carried by said turret; a vertically adjustable 35 outlet connection extending through the bottom of said receptacle; a valve in said connection; means for conducting fluid from said connection to the can upon said holder; and means for operating said valve by the vertical movement of said can.

2. A can filling machine comprising a rotating turret; a reservoir carried thereby; means for filling a can from said reservoir; a valve head positioned centrally above said 45 reservoir; a connection between said head and said reservoir, adapting them for independent rotative movement; a valve in said head; a float in said reservoir adapted to operate said valve; a flexible conduit connected with said head; and a plurality of fluid supply pipes adapted for separable connection with said flexible conduit.

3. A can filling machine comprising a rotating turret; a reservoir carried thereby; 55 means for filling a can from said reservoir; a valve head positioned centrally above said reservoir, a connection between said head and said reservoir, adapting them for independent rotative movement; a valve in said head; a float in said reservoir adapted to operate 60 said valve; a plurality of fluid supply connections disposed radially about said head; and a conduit communicating with said head and adapted for separable attachment with 65 said supply connections.

4. A can filling machine comprising a rotating turret; a reservoir carried thereby; a measuring receptacle suspended below said reservoir and communicating therewith; a vertically adjustable outlet tube extending 70 through the bottom of said receptacle; a valve in said tube; a vertically movable can holder carried by the turret; and means for operating said valve by the vertical movement of the can.

In testimony whereof I have signed my name to this specification.
